UNITED STATES PATENT OFFICE.

GEORGE J. CLINE, OF GOSHEN, INDIANA.

FENCE-WEAVING MACHINE.

SPECIFICATION forming part of Letters Patent No. 379,100, dated March 6, 1888.

Application filed October 22, 1887. Serial No. 253,110. (No model.)

To all whom it may concern:

Be it known that I, GEORGE J. CLINE, a citizen of the United States, and a resident of Goshen, in the county of Elkhart and State of Indiana, have invented certain new and useful Improvements in Fence-Machines; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a side elevation of my improved machine. Fig. 2 is a front elevation of twister-frame. Fig. 3 is a plan view of the picket device R. Fig. 4 is a front view of same. Fig. 5 is a vertical longitudinal section through center of cylinder J. Fig. 6 is a horizontal section on line $\alpha\alpha$, Fig. 1. Fig. 7 is a side elevation of the tension device.

The invention relates to improvements in machines for making wire-and-picket fences; and it consists in the construction and novel combination of parts, hereinafter described, illustrated in the accompanying drawings, and pointed out in the claims hereto appended.

The invention pertains to both the tension and the twisting mechanism, the former of which will be first described.

Referring to the drawings, A designates an upright of proper height, rising at a suitable point from the base-frame a, composed of longitudinal and transverse pieces, as shown, and held stiffly upon the base-frame by the inclined brace-rods a' a', as shown. To the facing edge of the upright are attached at proper points the tension devices B, each of similar construction and each intended to produce the requisite tension in one of the pairs of wires used in making the fence. Each tension device B consists of a rectangularly-bent bracket-plate, b, having bearings in the ends of its arms for the reel-shaft C, one end of which is extended outside the corresponding arm, and squared to receive and be turned by a crank-handle, c. The reel-shaft is held in its bearing by a circumferential shoulder at one end and a transverse pin at the other end outside of the arms of the bracket.

D is a bolt having an eye, d, in which the

reel-shaft rests centrally and turns, the wires X X being wound in the usual manner on each side of said eye. The nut D passes through the transverse part of the bracket-plate and through a suitable opening in the upright and engages a nut, E, on the surface of the bracket, and a similar nut, e, on the outer edge of the upright. By screwing outward the nut E and screwing inward the nut e the eye d may be made to bind more or less upon the reel-shaft, and thereby increase the tension of the wires when leaving the reel-shaft to give the proper rigidity to the fence.

By means of the handle c the coils of wire 65 may be rolled on the respective reel-shafts.

The twisting mechanism is as follows:

F is a twister-frame composed of the two pairs of parallel side bars, f f', connected at their upper and lower ends, the bars on one side being connected together their entire length, but those on the other side separated between the connecting pieces at their upper and lower ends.

g g are pieces connected to the edges of the frame F at the feet of the bars f f' by a bolt, G, which passes through them at proper points and engages a nut on the outer side of the corresponding piece, so that the said pieces turn stiffly on the lower end of the frame.

H H are similar rollers journaled in the ends of the pieces g on opposite sides of the frame, and which permit the latter to be moved back and forth, when necessary, in making a fence.

The twisting devices connected to the frame 85 F are of similar construction, with the exception of the one from which the others are actuated, and which has certain additions to said construction, hereinafter described. Each of said devices consists of two similar side pieces 90 or plates, I I, resting, respectively, against the opposite sides of the frame, and having their ends connected at the opposite edges of the frame by the bolts i, which pass through suitable openings in said ends, with their heads 95 resting against the outside of one piece I and engaging nuts i', which rest against the outside of the opposite piece. The two opposite pieces can, by unscrewing the said nuts, be slid on the frame, and then, by screwing up the 100 nuts, secured at the desired position thereon.

Each piece I is enlarged at its central por-

tion, and provided in said enlargement with a bearing for the rotary hollow cylinder J, upon which, inside the frame F, is secured the chain-wheel j, all of said wheels being connected and actuated by a chain, K, that is crossed between adjacent wheels, so that said adjacent wheels rotate in opposite directions.

Each hollow cylinder has passing centrally through it a bolt, L, which passes also centrally through a cap, M, fitting upon one end of the cylinder, and having two opposite openings, m m, at equal distances from its center to receive the wire from the corresponding tension device. The tapped end of the said bolt passes centrally through a piece, l, which fits in the rabbeted end of the cylinder and engages a nut, l', on the outside of said piece, so that the bolt and twisting-cap M can be held securely in position and turn with the cylinder.

20 The actuating twisting device has its pieces I extended beyond the closed edge of the frame F, and has in the ends of said extensions bearings for the shaft N, which is extended and squared on the side opposite the twisting-cap M for the reception of the crank-handle C'.

O is a chain-wheel on said extended end of the shaft, and P is a similar chain-wheel on the extended end of the corresponding hollow cylinder. The wheels O and P are connected by the chain Q, so that by rotating the shaft N by its crank handle C' the said chain-wheels are rotated, and consequently the chain-wheels J, also by means of the chain K, thus twisting the adjacent pairs of wires from the tension-frame in opposite directions.

35 R R are the devices by means of which the distance of the pickets from the twisting-frame is adjusted. These devices each consist of a transverse bar or base-piece, S, and 40 two similar blades, T, having at one end the trunnions t, semicircular in cross section and resting in corresponding bearings, s, in the inner side of the bar S. The said bearings are situated near opposite ends of the bar S, and are crossed by the longitudinal slots s', which are not aligned, so that the blades T, which pass through said slots, may be turned across each other. The said blades are provided with corresponding longitudinal series 45 of adjusting-openings t', so that by passing a suitable pin, t'', through the meeting openings in said series the blades may be crossed at different angles. The said devices R are secured to the side of the twisting-frame F, on which 50 are the pieces l in the cylinder end, one being situated below the twisting device and one thereabove, so that the pickets may be placed

between the outer ends of the blades T, and their positions from the frame F adjusted by the means described.

60 The manner of adjusting and holding the wires is the same as in similar machines of this class, and after the wires have been twisted on the edge of one picket the twisting-frame is moved far enough therefrom to insert another picket between the wires, which have their tension varied as desired by the described means.

It is obvious that after a picket has been secured by the twist the next picket is secured by an opposite twist—that is, the motion of the crank C' is reversed and brought back to its original position.

Having described my invention, I claim—

1. In a fence-machine, the tension mechanism composed of a frame provided with an upright, and the tension devices secured to said upright, and each consisting of the rectangularly-bent bracket-plate, the reel-shaft journaled in the ends of the arms of said bracket-plate, and having one extended end squared to receive a crank-handle, the eye-bolt with its eye surrounding the central part of the reel-shaft and passing centrally through the bracket-plate and upright, and the nuts 75 engaging the tapped ends of the eyebolt respectively on the surface of the bracket-plate and on the outer edge of the upright, substantially as specified.

2. The combination, with the twister-frame, 90 of the twisting devices vertically adjustable on said frame, and each provided centrally with a chain-wheel, j, the chain K, crossing between adjacent twisting devices, the chain-wheel P, secured to the extended end of the 95 hollow cylinders of one of the twisting devices, the chain-wheel O on the shaft N, journaled in the extended ends of the pieces I of the twisting device carrying the chain-wheel O, the chain p, and the crank-handle C, engaging 100 the squared extended end of the shaft N, substantially as specified.

3. The combination, with the twister-frame, 105 of the picket-adjusting devices, each composed of the bar S, having the bearings s, and slots s', and the blades T, provided with the semi-cylindrical trunnions t, the adjusting-openings t', and the pin t'', substantially as specified.

In testimony whereof I affix my signature in presence of two witnesses.

GEORGE J. CLINE.
